Primary Examiner — Cynthia M Chin*(74) Attorney, Agent, or Firm* — Greg Carr; Daryl Wright(57) **CLAIM**

We claim the ornamental design for a body for a model vehicle, as shown and described.

DESCRIPTION

FIG. 1 is a front elevation view of a body for a model vehicle;

FIG. 2 is a front elevation view thereof, with the bumper guard removed;

FIG. 3 is a left side elevation view thereof;

FIG. 4 is a rear elevation view thereof;

FIG. 5 is a top plan view thereof; and,

FIG. 6 is a top, left, front perspective view thereof.

Structural elements depicted by broken lines have been shown for the purpose of illustrating portions of the body for a model vehicle that form no part of the claimed design. The appearance of the right side of the body for a model vehicle is a mirror image of the left side of body for a model vehicle.
